UNITED STATES PATENT OFFICE.

JACOB D. SPANG, OF JACKSONVILLE, FLORIDA.

GAME-BOARD.

SPECIFICATION forming part of Letters Patent No. 271,530, dated January 30, 1883.

Application filed December 28, 1882. (No model.)

To all whom it may concern:

Be it known that I, JACOB DARING SPANG, of Jacksonville, in the county of Duval and State of Florida, have invented a new and useful Improvement in Game-Boards, of which the following is a full, clear, and exact description, reference being had to the annexed drawings, forming part of this specification.

This invention is an improvement on the game-board shown and described in Letters Patent No. 148,995, which were granted to me under date of March 24, 1874.

In the drawings, Figure 1 is a plan view of the game-board. Fig. 2 is a longitudinal section of the same, and Fig. 3 is a view representing the board folded.

The game-board represents a portable toy race-track for field and parlor amusement, in which A indicates the race-field, track, or platform, which is inclined when in use, and surrounded by a mimic fence or inclosure, B. C is the starting-station, in which balls D are placed to represent horses, and the balls are severally marked, so that one can be distinguished from another. The number of balls is to be optional; but I prefer to use thirty-six. The gate E, instead of being hinged to the bottom of the track, as in my former invention, is adapted to slide in grooves *ee* in the walls of the inclosure B, so that it can be lifted to let the balls pass under it and roll down the track by the force of their own gravity. As the balls pass out from the station C they will first encounter posts F, arranged in transverse rows, with the posts of one row out of alignment with those of another. The balls will be retarded more or less by the posts, as well as diverted from their course, but will all come to the cross-hurdle G, up and over the inclined surface of which they will roll and pass on between another series of posts, F', arranged like those above described. Some of the balls are likely to be thrown to one side or the other of the track, and to prevent them from remaining at the side I provide posts F'', arranged in rows inclined toward the center of

the track, by which the balls may be guided inward toward the main portion of the track. A second hurdle, G', is arranged at or near the mid-length of the board, over which the balls will be conducted to a section in which are a series of stops or stables, H, arranged in transverse rows, in the manner of the posts F and F'. Some of the balls will be caught and detained in these stops, while others will escape, though interrupted by the intermediate posts, F³, and pass over the third and last hurdle, G², to another section having stops H, arranged in the manner already described. Most of the balls will be detained in the stops, while one or more will probably reach the goal I. Those that succeed in reaching goal I will not arrive simultaneously, but successively, thus enabling the one arriving first to be accounted the winner and to score the highest number or count in the game, while others are allowed a count according to their relative time of arrival. At the sides of the first section of stops are two other series of guide-posts F², adapted to turn the balls inward from the sides in the manner above set forth.

The hurdles G G' G² are constructed of sheet metal bent in the forms shown and secured to the surface of the track. Around the edges of the hurdles may be inserted stakes or pegs K to increase the similitude to an ordinary race-course.

What I claim as new is—

1. The combination, with the board, the balls, the posts, hurdles, and stops, of the posts F², arranged in rows inclined inward toward the center of the board, as and for the purpose described.

2. The combination, with the board having inclosure B, provided with grooves *ee*, of the gate adapted to be lifted to let the balls pass, substantially as shown and described.

JACOB D. SPANG.
